HOT STAMPING DEVICE

Herman Gould, Brooklyn, and Frank Ackerman,
Bronx, N. Y.

Application February 28, 1933, Serial No. 658,900

3 Claims. (Cl. 101—27)

Our present invention relates to a hot stamping device which is primarily intended for stamping, imprinting or embossing plain, colored, lustrous or metallic foil letters, monograms, designs, insignia, etc., upon articles of stationery such as writing paper, announcements, cards and the like. It may, however, also be used and is adaptable for similarly treating articles of merchandise made of paper, fibre, leather, textile and analogous materials.

The primary object of our invention is to provide a device of the character described which is exceeding simple in construction and operation so that an unskilled person can efficiently operate it after a few minutes instruction and which can be manufactured and sold at a price which should enable every stationery and leather goods dealer to acquire one. A further object is to provide a device of the character described wherein the type or dies are visibly carried by the device in front of the operator so that the setting up and resetting of said type or dies can be accomplished in the least possible time without the operator leaving his station. A further object is to provide an improved supporting means for the color strip or ribbon carrying the imprinting ink or metal foil and automatic feeding means therefor. A still further object is to provide a novel readily renewable cushioning element for the type or die when making the impression on the article being stamped.

The foregoing and other objects of our invention will be apparent from the detailed description of the device which follows when considered in conjunction with the accompanying drawings, wherein:

Figure 1 is a front elevation of the device embodying our invention, parts thereof being broken away to better show the details of construction.

Fig. 2 is a side elevation of Fig. 1 when viewed from the left end thereof, parts thereof being broken away.

Fig. 3 is a fractional rear elevation of the ribbon feeding means.

Referring to the drawings, let A indicate a substantially C-shaped frame carried by and preferably formed integrally with a substantially conical base member B. The upper arm of the C-shaped frame is formed with a depending portion 2a having a transverse recess 3a therethrough for accommodating heating means preferably in the form of an electric resistant element C which is removably carried thereby. The front and rear sides of the member 2a are inclined inwardly from the base thereof as indicated at 4a to provide a supporting and guiding means for a palette or type holding means D.

The palette D is formed with a dovetailed recess or slideway for engaging over the tapered sides 4a and is formed on its under side with a

socket member d within which type elements or dies E may be suitably held and clamped in position by a clamping screw 2d. In its front wall, the palette D carries a handle 3d the inner end of which screw-threadedly engages through said wall and is adapted to engage the member 2a to clamp the palette in position thereon.

The base member B at its top supports a table b and depending from said table and extending centrally through said base member is a stud 2b formed with a rack 3b. Transversely extending through an opening in the base B is a shaft F adjacent one end of which is provided with a pinion f in engagement with the rack 3b. To the opposite end of the shaft F there is connected an operating lever 2f which is held to the shaft by a clamping screw 3f.

Mounted on the table b is a platen G which is movable upwardly toward the palette D as the operating handle 2f is moved downwardly. On its under face the platen carries a depending pin g which extends through an opening in a lug 4b whereby the platen is held against rotational movement with respect to the base. At the lower end of the pin g is a washer 2g held thereon by a screw 3g and encircling said pin between said washer and the under face of the lug 4b is a helical spring 4g which is adapted to return the platen downwardly and move the operating lever 2f upwardly upon the completion of an imprinting operation. At the rear of the platen G there are mounted two plates 5g each of which carries a stud or pin member 6g which extends in parallel relation over the top face of the platen.

Mounted upon the top face of the platen and adapted for adjustment forwardly and rearwardly with respect thereto is a gauge bar H which at each end is formed with an opening through which one of the pins 6g extends, which pins function to guide the gauge bar in its movements. To fix the gauge bar in any adjusted position upon the platen thumb screws h extend through the ends thereof for clamping engagement with the pins 6g. A second gauge bar H' is mounted to slide in a guideway 2h on the under face of the platen and is adapted to be held in adjusted position by a clamping screw 3h. Spring clips 4h are carried by the gauge bar H and are adapted to receive and hold the paper to be stamped while the platen is being raised and lowered.

Supported on the underside of the platen through the medium of a bracket J and a pin j carried thereby is a roll of heavy paper 2j which is adapted to engage over the face of the platen below the type or die and function as a cushioning element therefor when making an impression on the article being stamped. In order that the top face of the platen may retain its smooth surface condition for accommodating the article to be stamped it is formed with a depre-

sion 7g having a depth substantially equal to the thickness of the cushioning strip 3j from the roll 2j. To accommodate the cushioning strip 3j the platen is formed with guide slots 8g and 9g and 5 to hold said strip within said depression any suitable means may be employed, for example a sheet of paper may extend across the strip and be fixed to the platen. The free end of the cushioning strip which extends through the slot 9g 10 may also be held if desired by any suitable means or may be left free for engagement by the fingers of an operator to pull the same over the platen to present new portions of said strip below the stamping die when required.

15 Secured to the top bar of the C-shaped frame is a carrying member K, near one end of which is mounted a spindle k extending forwardly therefrom upon which in turn is mounted a disk 2k, and a roll of imprinting material L which may 20 be of any desired character which will permit a transfer of colored ink or metallic foil therefrom to an article being stamped under the influence of heat and pressure. To provide the necessary frictional resistance to said roll L to 25 permit unwinding thereof under tension a second disk 3k is mounted on said spindle and held in frictional engagement against the roll L by any suitable means, for example, a clamping ring 4k. At the opposite end of the member K upon a 30 depending lug thereof is mounted a spindle 5k upon which in turn is rigidly mounted a friction roller M. In superposed relation to the roller M is a second friction roller N carried by an arm 6k pivoted at 7k, said roller N being held against the 35 roller M under the tension of a spring 8k, one end of which is connected to an end of a bar 6k and the other end of which is detachably secured to a pin 9k.

Also carried by the spindle 5k is a ratchet wheel 40 O, movement of which by a gravity activated pawl P causes movement of the roller M to draw the color strip l from the roll L between the rollers M and N. The pawl P is pivotally mounted at p to one end of a link Q, the other end of which 45 is also fixedly mounted on the spindle 5k. For moving the link Q and with it the ratchet wheel O there is provided a rod R, one end r of which is fixed to the platen G and the other end 2r of which is pivotally connected to the link Q 50 intermediate its ends. For varying the throw of the pawl P the link Q may be provided with several openings q to which the end 2r of the rod R may be connected. For rendering the feeding means for the strip l inoperative, it is merely necessary to throw the pawl over on its pivot as 55 shown in dotted lines in Fig. 3.

Mounted upon the member K in inclined relation to the front of the device is a type case S consisting of a base element s and a top plate 60 2s having a plurality of horizontal rows of aligned openings for the type elements E, the top plate being spaced from the bottom plate by spacing elements 3s. Preferably there are three horizontal rows of openings to accommodate alphabets 65 of monogram type, which are provided in three forms, namely, a left, a center and a right monogram of each letter. The horizontal rows are accordingly designated L, C and R to indicate the monogram type in said respective rows of 70 openings. Of course additional spaces may be provided for specific dies, insignia, etc.

In the operation of the device a suitable monogram is prepared from any three letters taking a left, center and right monogram type of the desired letters. This monogram or other specific

die is positioned within the palette D and held therein by the clamping screw 2d. The palette is then mounted on the member 2a and clamped thereon through the operating handle 3d. The palette and its type are then heated by the electric heating element C by turning on the current therethrough. The color strip l is then fed from the roll L around the guides 6g and then up between the friction rollers M and N. The cushioning strip 3j from the roll 2j is threaded through the slot 8g in the platen and disposed in the recess 7g and held therein as hereinbefore described. The gauge bar H is then adjusted for the particular size sheet to be stamped and upon feeding such sheet to the platen under the clips 4h and moving the platen upwardly into contact with the heated type E the color medium or metallic foil from the strip l will be transferred to the sheet, whereupon by releasing the operating handle 2f the platen is returned to its lower position by the coil spring 4g. As the platen recedes, the strip l is fed a predetermined amount by the ratchet and pawl construction. These operations are then repeated until the particular quantity of paper is stamped. The end 9g of the cushioning strip is then gripped to draw a length of paper across the platen to present a fresh cushioning surface to the type for the next job. To perform the operation upon a second job the operator without leaving his station can quickly reset the palette from the type case in front of him.

While we have shown and described a preferred embodiment of our invention it is to be understood that changes may be made therein without departing from the spirit thereof.

110

What we claim is:

1. A stamping device of the type described comprising a frame having mounted thereon a platen, type holding means, means for causing movement of said platen relatively to the type holding means for stamping operations, a color strip movably disposed over the platen in spaced relation thereto, a gauge bar adjustable over said platen and guide members carried by said platen and disposed over the face thereof adapted to function to guide both the color strip and the gauge bar.

2. A stamping device of the type described, comprising a frame having mounted thereon a platen, type holding means, means for causing movement of said platen relatively to the type holding means for stamping operations, a cushioning strip disposed upon the platen to lie substantially flush therewith beneath the type holding means, and said cushioning strip being movable relatively to the platen to present a fresh portion thereof beneath the type holding means as desired.

3. A stamping device of the type described, comprising a frame having mounted thereon a platen, type holding means, means for causing movement of said platen relatively to the type holding means for stamping operations, a cushioning strip disposed upon the platen beneath the type holding means, the platen having a depressed portion for accommodating the cushioning strip so as to lie substantially flush with the top of the platen and said cushioning strip being supplied from a roll on the underside of the platen and being movable relatively to the platen to present a fresh portion thereof beneath the type holding means as desired.

HERMAN GOULD.
FRANK ACKERMAN.
